[73] Assignee: Filter Queen Ltd., Etobicoke,
Canada

[57] CLAIM

The ornamental design for a housing for a central vacuum cleaner, substantially as shown.

DESCRIPTION

FIG. 1 is a front perspective view of a housing for a central vacuum cleaner showing my new design;

FIG. 2 is a front elevational view thereof;

FIG. 3 is a side elevational view thereof;

FIG. 4 is a bottom plan view thereof;

FIG. 5 is a top plan view thereof;

FIG. 6 is a rear elevational view thereof; and

FIG. 7 is a side elevational view thereof, of the opposite side of FIG. 3.
